UNITED STATES PATENT OFFICE.

EDWARD R. BARRETT, OF DETROIT, MICHIGAN, ASSIGNEE TO BURROUGHS ADDING MACHINE COMPANY, OF DETROIT, MICHIGAN, A CORPORATION OF MICHIGAN.

ADDING AND LISTING MACHINE.

1,214,060.

Specification of Letters Patent. Patented Jan. 30, 1917.

Application filed January 6, 1913. Serial No. 740,442.

To all whom it may concern:

Be it known that I, EDWARD R. BARRETT, a citizen of the United States, residing at Detroit, in the county of Wayne and State 5 of Michigan, have invented certain new and useful Improvements in Adding and Listing Machines, of which the following is a specification.

The present invention relates to the 10 equipment of an adding and listing machine for doing what is commonly termed "split" work, which means multi-column work with the paper in one position so far as its lateral adjustment is concerned.

Ordinarily the so called splitting of an 15 adding machine is accomplished by interrupting or suspending the co-operative action between elements of the printing mechanism. The commonest form of printing mechanism for these machines is that 20 wherein hammers are normally retracted against spring pressure and the latches which hold them back are adapted to trip one another for the purpose of filling in 25 ciphers. These machines ordinarily do not have cipher keys and the cipher types are brought automatically to the printing position in all numerical orders and in any orders to the right of the highest digit of 30 the amount being registered and recorded, wherein no digits occur, the ciphers are printed as a result of the tripping of the hammer latch of some order to the left wherein a digit is printed. It is now a well 35 known expedient, for the purposes of the so called "splitting," to provide movable coupling devices between the latches and to equip the machine with keys or other manipulating devices for controlling such coupling devices so that at the desired point 40 or points the latches may be disconnected for the purpose of interrupting the automatic tripping.

The main object of my present invention 45 is to arrive at this so called splitting, and that to any extent desired as to location or number of splits or points of interruption, without relying upon any special construction of the printing or recording section or 50 department of the machine by which I mean the mechanism for making the impressions. I propose to accomplish the result primarily through a control of the setting of type carriers to present ciphers at the printing

line. I have above referred to the familiar 55 feature of these machines which has to do with automatically setting the cipher types. This ordinarily involves a one-step advance of all type carriers in numerical orders where digits do not occur in the amount 60 being registered and recorded. According to my present invention provision is made for blocking this usual preliminary one-step advance of type carriers and putting it under control of the operator to be regulated 65 according to the character of split work which he desires to perform. Thus by a preliminary adjustment the operator is enabled to put the machine in a splitting condition by latching all of the type carriers, 70 and then by selective setting of denominationaly arranged devices the condition can be modified so that the result of depressing an amount key representing the first digit of an amount to be recorded will unlatch 75 the associated type carrier and a series of type carriers to the right up to a certain predetermined point. The result is that automatic setting of cipher types will thereafter occur only throughout the predetermined range, and separate items may be 80 printed in one or more parallel vertical columns without intervening ciphers.

In the drawings which accompany and 85 form part of this specification, Figure 1 represents in left side elevation an adding machine of the well known Burroughs type equipped with mechanism for embodying my invention; Fig. 1^a is a fragmentary left side elevation of certain parts which appear 90 for the most part in dotted lines in Fig. 1, Fig. 1^a illustrating a different condition from that depicted in Fig. 1, to wit the condition which exists when the total or subtotal key of the machine has been depressed 95 and the machine is nearing the close of a totaling operation; Fig. 1^b is a similar view showing the condition at the close of such operation, the total key being still depressed; Fig. 2 is a sectionalized left side 100 elevation of the front portion of the machine illustrating a normal condition; Fig. 3 is a somewhat similar view illustrating the split condition; Fig. 4 is another similar view illustrating a still different condition, 105 to wit that for preventing printing of a total under one or more columns; Fig. 5 is a view of the same general character on a

somewhat larger scale illustrating the relationship of parts resulting from preparatory manipulation for putting the machine in splitting condition but with the manipulating device for actually effecting the split, at normal; Fig. 6 is a cross section on the line 6—6 of Fig. 5; Fig. 7 is a perspective view of a coupling bail; Fig. 8 is a section- 5 alized plan view on three planes, one above the upper keyboard plate, another between the two keyboard plates, and the third below the lower keyboard plate; Fig. 9 is a vertical cross section taken substantially on the line 9—9 of Fig. 8.

10 15 The numeral 291 designates the usual amount keys which operate in the familiar manner to set stops for limiting the descent of the segmental racks 610. The latter are mounted as usual upon the front ends of levers 611 through a slot-pin-spring connection to permit one-step movement of any rack relative to its supporting lever and vice versa. Levers 611 carry the usual type plate 618 at their rear ends for striking 20 25 30 35 40 45 50 55 60 65 against a roller platen 3 under actuation by hammers 715. Hammer latches or detents 717 normally restrain the hammers as usual, and pawls 718 individually trip said latches provided associated levers 611 have moved far enough to present digital types at the printing line; otherwise tails of the pawls encounter shoulders of the levers and the pawls are rocked thereby so as to miss the latches. The latter however have the usual overlapping tails so that one may trip another from left to right throughout the series. All of this is old and well known and it need merely be noted at this point that in the normal position of the type carriers the uppermost types, which are the cipher types, are below the printing line and the plates carrying these types are below the paths of movement of the hammer heads so that release and discharge of hammers with the type carriers so held would not result in any printing. I mention this here because in carrying out my invention, I take advantage of this condition to prevent the printing of ciphers beyond the point of split. The first thing to be noted as to change in form of familiar parts of this machine is that each of the levers 611 near its front end is formed with an upstanding arm 611^a having the character of a hook in that its upper extremity is undercut at the rear. Upon one of the cross rods 200^a under the keyboard which ordinarily supports the key operated bell cranks 217, there are loosely hung depending pawls 10, one for each hook 611^a (see Fig. 9), the laterally turned terminal portions or feet of these pawls being adapted to engage said hooks for the purpose of blocking the usual one-step movement of the levers 611, which movement 65 would result in bringing the cipher types to the printing line. Rearwardly extending upper arms 10^b of these pawls carry roller studs 10^c which are adapted to be acted upon by substantially V-shaped cam portions 13^a of disks 13 secured to a rock shaft 200 which at the right of the machine carries a handle 14 projecting through a slot of the keyboard (Fig. 8), alongside an index plate 18 inscribed "Nor" at one place and "Split" a space in rear thereof. With the handle 75 forward opposite the inscription "Nor" the pawls 10 are all rearward as illustrated in Fig. 2, whereas the result of throwing the handle back to register with the inscription "Split" is to cause the cam projections 13^a to operate upon the roller studs 10^c and throw all of the pawls 10 forward so as to engage their feet 10^b with the hooks 611^a as illustrated in Fig. 3. It will be seen by reference to Fig. 3 that when the handle 14 has been so thrown rearward, the cam projections 13^a will have passed so far forward of the studs 10^c that, in the absence of restraining means, the pawls 10 would immediately swing back to normal under the action of 90 their retracting springs 11. However the pawls are caught and held in their forward position by special latching devices, one of which appears in perspective in Fig. 7. These are in the form of yokes or bails 95 strung on a cross rod 200^b and tending by gravity to assume positions such as shown in Fig. 5 wherein they latch the pawls 10 in their forward position. Normally these latching yokes or bails are swung upward 100 and rearward as shown in Fig. 2, being so held by the pawls themselves. The construction of all of them is the same so that a detailed description of one will suffice.

105 Referring to Fig. 7 the yoke or bail comprises a transverse member 15 and depending side arms 15^a and 15^b, the former having a cam finger 15^d and a hook 15^e in rear thereof. The associated pawl 10 has a forwardly extending arm 10^d with a laterally turned 110 portion 10^e to engage the hook 15^e and an upwardly and forwardly extending branch with a stud 10^f to ride upon the cam finger 15^d. Normally this stud engages the high 115 part of the cam finger as shown in Fig. 2 thereby holding the latch yoke upward and rearward. When the pawl is swung forward said stud passes into a recessed portion of the side arm 15^a above the cam finger and the yoke drops so that its hook 15^e becomes engaged with portion 10^e of the pawl as shown in Figs. 3 and 5.

120 125 130 The parts above referred to as latch yokes or bails form parts of the couplings whereby the tripping of one pawl 10 (as herein-after described) results in the tripping of other pawls to the right up to the point of split, and the construction here shown provides for establishing the split between any two adjacent numerical orders. It will be

understood of course that rearward swinging of any latch bail or yoke will release the associated pawl so as to unlatch the associated type-carrying lever and permit it to 5 partake of its usual movements including the one-step advance for setting up a cipher type. Further than this the yokes are coupled together so that one will displace another from left to right. To this end the 10 left hand side piece 15^b of each yoke, except the one farthest to the left, has a rearwardly extending branch 15^c with a leftwardly projecting ear 15^d. Then there is mounted upon the right side piece 15^a of each yoke, except 15 that farthest to the right, a coupler piece 16, the shorter of the two upwardly extending arms of which has a shoulder 16^a to engage the ear 15^d of the adjacent yoke. The coupler piece is pivoted to its yoke so as to provide for uncoupling the two yokes so normally engaged, as illustrated in Fig. 5, the shoulder 16^a being thrown rearward of the ear 15^d to effect the uncoupling, as illustrated in Fig. 8. The longer one of the two 20 arms of the coupler piece 16 projects through the lower keyboard plate 212 alongside an associated slide piece 17 set in between the lower keyboard plate and the upper keyboard plate 212 and having a laterally projecting lip 17^a to act upon said arm. It will be understood of course that there is one of these slide pieces for each line of 25 division or split. They are located with respect to the amount keys centrally between the rows of keys and forwardly thereof, having finger pieces 17^b projecting through slots in the upper keyboard plate 212 as shown most clearly in Fig. 8. The before-mentioned index plate 18 is extended along- 30 side the slot of the finger piece farthest to the right and is inscribed, as shown in Fig. 8, with the abbreviation "Nor," the word "Split" and the words "No total" arranged in that order front to rear. From this it 35 will be clear that the forward position of the various finger pieces is the normal one, the intermediate position is the splitting one and the rearmost position is one which results in the preventing of the printing of a 40 total. In order to make certain the three conditions of these adjustable slides, each one has a stud 17^c (Fig. 5) for engaging the depressions of a spring detaining strip 17^d. 45 Each of the coupler pieces 16 is drawn forward to effective position by a spiral spring 16^e which connects an ear of the longer arm to the transverse portion 15 of the yoke, as clearly illustrated in Fig. 7, and when the associated slide 17 is moved 50 rearward and its lip 17^a acts upon the coupler piece, the latter is swung upon its pivot in opposition to the spring, though this spring of course is not strong enough to dislodge the stud 17^c from the notch of the 55 spring strip 17^d. Assuming one or more of the slides 17 to have been thrust rearward to the intermediate position and the associated coupler member 16 thus forced rearward out of engagement with the adjacent latch yoke, it will be obvious that tripping of one latch 70 yoke by another will cease with the tripping of the yoke carrying the displaced coupler piece. It follows that the pawl 10 of the next numerical order to the right will remain engaged with the associated type carrying lever and the latter will be kept out of cipher setting position in an ensuing operation of the machine so that the printing of ciphers will stop with the printing in the denominational order to which the latch 75 yoke belongs that has the displaced coupler piece.

The release of type carrying levers from restraint imposed upon them by the pawls 10 is effected through depression of the amount keys. To this end the left side piece 15^b of each latch yoke extends downwardly in front of a shoulder 214^a on the detent slide strip 214 which is operated upon in the usual way by the amount key bell cranks 217. It will be understood that here, as in the usual Burroughs machine, the depression of the amount keys results in rearward thrust of the detent slide strips. When the handle 14 is thrown rearward to establish 80 a splitting condition of the machine, the resultant forward swing of the pawls 10 and drop of the latch yokes brings the forward edges of the extensions of the side pieces 15^b close up to the shoulders 214^a as illustrated 85 in Figs. 3 and 5. Therefore rearward movement of a slide strip as caused by depression of an amount key results in swinging the associated latch yoke rearward and disengaging its hook 15^c from the pawl so that 90 the latter swings rearward releasing the type carrying lever. The coupler piece 16 acting upon the ear 15^d of the adjacent latch yoke to the right swings that yoke rearward, also releasing the next pawl and type carrying lever, and this action continues until the yoke is reached whose coupler piece has 95 been displaced by the rearward setting of a slide 17 where it is desired to establish a split. Of course the same action will take 100 place in another division of the machine one or more orders to the right, and there may be as many divisions as desired within the denominational range of the particular keyboard.

It is not of course essential that the yokes have the cam fingers 15^d and the pawls 10 the studs 10^c, for necessarily rearward swinging of the yokes by the detent strips 214 must be sufficient in extent to unlatch the 105 pawls. However if the pawls did not then serve to further retract the yokes and hold them back (as they do through coaction of the studs 10^c and cam fingers 15^d) the yokes 110 would swing forward to some extent when 115

the detent strips were restored to normal and though this could not of course have the effect of relatching the pawls or seriously interfering with the functioning of any of the parts, yet it would mean repeated vibrations of the yokes as a result of rearward movement of the slide strips 214 whenever amount keys were depressed and when those strips were restored to normal in the successive itemizing operations of the machine. Such unnecessary vibration of yokes is obviated by extreme retraction effected through action of the studs 10^c upon the cam fingers 15^d whereby the yoke arms 15^b are carried out of reach of the shoulders 214^a of the slide strips 214 and so held.

Referring to the matter of transferring or carrying tens, which in a machine of the character here shown comes about as a result of one-step upward movement of racks 610 (permissible by reason of the same connection between these racks and the levers that provides for the one-step advance of the latter to set up ciphers), special provision is made for preventing any interference with the transfer action on account of the presence of the pawls 10 which, if engaged with the levers, though not obstructing the actual transferring rise of the rack, would prevent restoration of the transferring racks to normal. Thus, in addition to a release of pawls 10 through depression of the amount keys, they may be released through the rise of racks 610 in effecting transfers.

It will be understood in this connection that when establishing one or more splits in the ordinary uses of an adding machine it is customary to provide leeway for accumulation of totals one or more orders beyond the highest order of the different divisions into which the machine has been split. In carrying out my invention I have provided a special device for releasing the type carrying lever of a higher order into which a total may be extended, whenever the rack of such order rises to effect the transfer or carry. Thus I pivot upon the key-stop guide-plates 210 a series of similar bell cranks, a description of one of which will suffice for all. It comprises a forwardly extending arm 22 (Figs. 2, 3, 5, and 8) having a laterally turned end portion extending through a slot 211^a in one of said guide plates so as to be struck by the rack when the latter rises to effect a transfer; and an upwardly projecting arm 22^a which has a laterally turned portion extending in front of a branch 15^c of the left side piece of the associated latch bail. The two arms 22 and 22^a are united by a transverse portion 22^b which works between stop shoulders on one of the plates 210 (Fig. 5) whereby the movement of the bell crank is limited. It will be obvious from the above that when the rack rises and rocks the bell crank, the latter will displace

the latch yoke and thereby release the associated pawl 10, so that in the next operation of the machine the associated type carrying lever may move downward one step and restore the rack to the normal position, in which it is held by the usual transfer pawl.

Referring to the matter of restoring the machine to a normal position, it will be understood that in a series of operations under a split adjustment, some of the type carriers may remain latched, and in fact this is likely to be the case since ample provision is usually made for extending the totals and so certain type carriers may not be unlatched even as a result of carrying or transfer operations. I provide for the unlatching of any such type carriers by the act of throwing forward the handle 14. The disks 13 are formed with upper branches 13^b having laterally turned end portions adapted to act upon the rear arms 24 of levers journaled on the cross rod 200^a and having forwardly projecting arms 24^a underlying the laterally turned portions of the coupler pieces 16—to wit, the ears to which the springs 16^c are attached (Fig. 7). When the arm 14 is thrown forward the laterally turned portions of the disk-arms 13^b rock said levers so that their forward arms acting upwardly against said ears of the coupler pieces will rock the latches rearward and release any of the pawls 10 that have not therefore been released, and so release associated type carrying levers. The levers 24—24^a also have upwardly projecting arms 24^b which play a part presently to be described in connection with the subject of preventing printing of totals in certain orders.

Referring next to the matter of totaling operations, (see Figs. 1, 1^a, 1^b), it will be understood that the totaling system is the familiar one employed in Burroughs machines. The numerals 265 and 265^s designate respectively the total and sub-total keys which operate through familiar connections to so affect the accumulator controlling devices as to either keep the pinions 916 in mesh with the racks 610 during the descent of the latter and disengaged during their ascent, or engaged during both descent and ascent. Now since it might very well be that split work was to go on after striking of totals or sub-totals, I make provision for automatically relatching all of the pawls 10 in their forward positions at the conclusion of an operation of the machine for the taking of a total or sub-total. The total key bell crank lever 227 is as usual connected by the link 227^a to an arm 1400 secured to the rock shaft 1400^a. I mount loosely upon this rock shaft a bail composed of side arms 30, connecting tie-plates 30^b (Figs. 1, 2 and 9) and an outer cross rod 30^c adapted, upon the forward

swinging of this bail, to act upon branches 10^a of the pawls 10 and swing the pawls forward to effective position. The right hand side piece of said bail is extended below the shaft 1400^c, forming an arm 30^d to which is pivoted a pawl 31 adapted to be acted upon by a stud 311^a on the familiar full stroke sector 311. Arm 1400^c secured to the rock shaft 1400^a carries a stud 32 which 15 projects into a slot of the pawl 31. This slot has a curved upper or forward side and an angular rearward or lower side so that a short distance below its upper extremity it is wider than at other parts (Fig. 1^a). 20 Normally the pawl 31 is rocked rearward as to its upward end and forward as to its lower end as shown by dotted lines in Fig. 1, the stud 32 being then at the upper extremity of the slot and the stud 311^a of the full stroke sector being in rear of the lower part of the pawl.

A spring 33 connecting an upper portion of the pawl to the arm 1400^c tends to swing the pawl forward as to its upper portion 25 and rearward as to its lower portion. When the machine is operated without total or subtotal key depressed the arm 1400^c of course remains rearward and its stud, being engaged in the upper end of the slot of the 30 pawl 31, prevents said pawl from shifting its position. However, upon depression of the total or sub-total key the arm 1400^c is rocked downward and as its stud 32 passes into the wider portion of the pawl slot to 35 allow of swinging of the pawl under actuation of its spring 33 to the position shown in Fig. 1^a, though at the outset it is prevented from so doing because of continued contact or its lower portion with the stud 311^a of the full stroke sector. Upon the downward rocking of the latter in the ensuing operation of the machine, the pawl swings to the 40 position shown in Fig. 1^a, the angle of its slot coming in contact with the stud of the arm 1400^c to limit the movement. Then when the full stroke sector returns, its stud 45 encounters the end of the pawl and so swings the arm 30^d upward and rearward and the bail, of which that arm is a part, forward and slightly downward so that the cross rod 30^b of that bail swings all the pawls 10 forward into engagement with their respective type carrying levers (Fig. 1^b). Meantime the lower portion of the 50 slot 31^a traverses the stud 32 so that the latter, at the conclusion of the operation, is at the lower end of the slot as shown in Fig. 1^b. However, upon release of the total or 55 sub-total key the shaft 1400 of course rocks back to normal and the arm 1400^c swings rearward. In so doing its stud 32 acts with a camming effect upon the forward side of the slot of the pawl (said slot-side being eccentric to the shaft 1400 when the pawl is 60 out of normal) and forces the latter out of

engagement with the stud 311^a of the full stroke sector, whereupon a spring 30^c, applied to the bail, swings the latter rearward.

Obviously the above described resetting operation is advantageous in case a different subdivision of the machine is called for by the character of work to be handled following the clearing of the accumulator at the conclusion of the preceding work which has terminated with a total printing operation 75 leaving the accumulator clear. The resetting is useful also where work is to continue under the same split adjustment as before because it will have the effect of preventing the printing of any ciphers to the 80 left of items heading the new work. This might otherwise occur by reason of the release of typecarrying levers as a result of transfer or carrying operations. Thus in the event of a typecarrying lever in an order higher than those wherein amount keys have been operated, having been released through advance of its rack to effect a carry, that type carrier would still be unlatched and therefore when the first itemizing was 85 done after the totaling operation, a cipher would be printed to the left of the item and of course the extent to which accumulating had gone might be such as to cause the printing of several ciphers. This would be objectionable on account of the confusion it might cause occurring at the head of a list and would of course be prevented by the relatching of all of the type carriers as a result of the preceding total printing operation. Such printing of ciphers as a result 90 of carrying operations may occur during the listing of items but other items in the same column printed without any ciphers to the left will serve to obviate any confusion as to 95 the line of split or subdivision. Then the fact that type carriers which are unlatched as a result of transfer of carrying operations, remain unlatched until a totaling operation 100 has been performed, is important for the reason that when it comes to printing the total these particular racks must be free to descend distances determined by backward rotation of their intermeshing accumulating wheels 105 to zero. Furthermore the appearance of a 110 cipher to the left of the highest digit of an item may serve a useful purpose because of the very fact that it comes about as a result of a carrying operation. Thus it serves as an indication that there has been registration beyond the capacity of the wheels belonging to those orders wherein keys are in use, and therefore something in the nature of a warning to the operator against continuing to add items in one section of the 115 accumulator to the point of affecting the accumulation in the next adjacent section to the left.

While a similar action to that above described as to forward swinging of pawls 10 120

will take place when the total or sub-total key is depressed and the machine operated, in a normal condition, such action will have no effect to latch the pawls 10 in effective position, for the reason that the controlling handle 14 is forward and the latch bails or yokes are held up by the levers 24.

Referring next to the matter of eliminating total imprints, each of the slides 17 is movable to a third position corresponding with the inscription "No total" upon the plate 15, and when so moved will establish connections whereby depression of the total or sub-total key will latch up the associated type carrier preventing movement thereof to set up type for the total. To this end each of the slides 17 has at the rear a laterally turned foot 17^a (Fig. 4) adapted, when the slide is moved to its extreme rearward position, to operate upon a lever 20 carried by an arm 19 fastened to the rock shaft 204 to which the total key bell crank lever 227 is secured. There is one of the arms 19 for each slide 17 (see Fig. 8) and it will be obvious that whenever the total or sub-total key is depressed this series of arms will be swung downward. Normally the levers carried by said arms respectively are held forward as to their upper ends and rearward as to their lower ends by springs 20^a connecting their lower ends with the arms 19 (Fig. 2) so that these levers pass to the rear of laterally turned portions 10^a of the rearwardly extending arms of the pawls 10. However, when any slide 17 is moved to the third position, the associated lever 20 is rocked to the position shown in Fig. 4 wherein its lower end overlies the laterally extending portion 10^a of the associated pawl. Then when the total key is depressed and the arms 19 swung downward all pawls 10 of orders where slides 17 have been moved to the third position will be swung forward and will hold up the associated type carrying levers. Unless these levers move from normal position there will of course be no printing in those orders when the machine is operated with the total key depressed. In this operation the pawls 10 are not latched in effective position as it would not be desirable to continue the condition beyond the single totaling operation. Therefore the slides 17, besides acting to set the levers 20 in the manner already described, act also when moved to their extreme rearward position, to rock the levers 24. For this purpose the slides are equipped with studs 26 adapted to act upon the upstanding arms 24^a of said levers 24 and rock the same as illustrated in Fig. 4 so as to hold up the latch yokes 15 and thus prevent latching of the pawls 10 which are swung forward in the totaling operation. It will be understood that slides 17 will be thrust to the third position in all orders of the division wherein

the total imprint is to be eliminated. This thrusting rearward of the group of slides is not only a matter of simple manipulation but has the advantage of showing at a glance the extent of the division of the machine 70 wherein the printing is prevented.

Referring again to the automatic action of the latch yokes when permitted to swing down by reason of the pawl studs 10^a riding off the cam fingers 15^a and into the recessed portions of the latch yokes, it is preferable not to rely wholly upon gravity for bringing about engagement between the hooks 15^c and the laterally turned portions 10^a of the pawls. When a slide 17 has been moved rearward for establishing a split, the rearward rocking of the associated coupler 16 will cause some tensioning of the spring 16^c so that the latter will be tending to swing the latch yoke to latching position, and other latch yokes to the left will be similarly affected by reason of engagement between the laterally turned ears 15^f of successive latch yokes and shoulders 16^a of neighboring couplers 16. As to an extreme right hand division of latch yokes which of course would not be affected by the setting of a slide 17, a special spring 25 is provided (see Fig. 8), which spring connects the extreme right hand latch yoke with a fixed stud 25^a. This spring affects the yokes throughout the entire series when the handle 14 is thrown forward and no slides 17 have been moved rearward so that whether or not one or more slides have been set for splits before the handle 14 is swung forward to put the machine in splitting condition, there will be some spring tension tending to engage the latch yokes with the pawls and acting in aid of the gravity of the latch yokes whereby to insure a latching of the pawls in their forward positions. The spring pressure however is so light in any case as to add no appreciable resistance to depression of amount keys when this is to result in displacement 100 of latch yokes.

It will be seen that the above described construction is well calculated to carry out the object primarily stated but it must be understood that this construction is susceptible of considerable modification within the scope of my invention. An advantage of the latter as compared with those forms of splitting means which involve special constructions of printing or impression controlling 115 mechanism, is that I am able to locate the handles of my splitting structure at the front of the machine where they can be most conveniently manipulated and where they most readily indicate conditions as to 120 denominational division, while at the same time the interior splitting mechanism is closely adjacent so that short and direct connections can be made, whereas the printing mechanism is usually remote from the front 125 130

of the keyboard of these machines and in case of location of splitting handles or keys there, when the interior splitting mechanism is incorporated in the printing department 5 of the machine, long and indirect operating connections are necessary and there are apt to be attendant difficulties in assembling owing to lack of room for accommodating such connections.

10 I claim:

1. In a machine of the character described, the combination with manipulative amount-determining devices, a prime mover, and type carriers adapted normally to partake of one-step movement for setting up ciphers; of settable means for detaining said type carriers out of cipher-setting position, means for effecting successive release of the type carriers by the amount-determining devices; 15 and means for interrupting at will the successive release of said type carriers.

2. In a machine of the character described, the combination with manipulative amount-determining devices, a prime mover, and type carriers adapted normally to partake of one-step movement for setting up ciphers; of pawls collectively settable to detain said type carriers; latches to hold the pawls set, said latches individually displaceable by the amount-determining devices; couplers between the latches; and manipulative coupler-displacing means.

3. In a machine of the character described, the combination with manipulative amount-determining devices, a prime mover, and type carriers adapted normally to partake of one-step movement for setting up ciphers; of normally retracted pawls for detaining said type-carriers; manipulative means for moving said pawls to engaging position; latches to hold said pawls in such position, said latches individually displaceable by the amount-determining devices; couplers between the latches; and manipulative coupler-displacing means.

4. In a machine of the character described, the combination with manipulative amount-determining devices, a prime mover, and type carriers adapted normally to partake of one-step movement for setting up ciphers; of normally retracted pawls for detaining said type-carriers; manipulative means for moving said pawls to engaging position; latches normally retracted by said means and adapted upon operation thereof to engage said pawls, said latches individually displaceable by the amount-determining devices; couplers between the latches; and manipulative coupler-displacing means.

5. In a machine of the character described, the combination with manipulative amount-determining devices, a prime mover, and type carriers adapted normally to partake of one-step movement for setting up ciphers; of pawls collectively settable to detain said type

carriers; latches to hold the pawls set, said latches individually displaceable by the amount-determining devices; couplers movably mounted upon the latches and operatively connecting them; and manipulative 76 coupler-displacing means.

6. In a machine of the character described, the combination with manipulative amount-determining devices, a prime mover, and type carriers adapted normally to partake of one-step movement for setting up ciphers; of pawls collectively settable to detain said type carriers; latches to hold the pawls set, said latches individually displaceable by the amount-determining devices; couplers movably mounted upon the latches and spring-connected thereto and operatively connecting them; and manipulative coupler-displacing means.

7. In a machine of the character described, the combination with manipulative amount-determining devices, a prime mover, register wheels, type carriers, and racks thereon, the type carriers and racks being relatively movable for transfer purposes and for setting up 80 ciphers; of settable means for detaining the type-carriers out of cipher-setting position, means for effecting successive release of type-carriers by amount-determining devices; means for interrupting the successive 85 release of said type carriers; and means for effecting release of a type-carrier by movement of its rack relative thereto.

8. In a machine of the character described, the combination with manipulative amount-determining devices, a prime mover, register 100 wheels, type carriers, racks thereon, the type carriers and racks being relatively movable for setting up ciphers, and totalizing means; of settable means for detaining said type carriers out of cipher-setting position, means for effecting successive release of the type carriers by the amount-determining devices; means for interrupting at will the successive 105 release of said type carriers; and means for resetting the aforesaid settable means by the totalizing means.

9. In a machine of the character described, the combination with manipulative amount-determining devices, a prime mover, register 110 wheels, type carriers, racks thereon, the type carriers and racks being relatively movable for setting up ciphers, and totalizing means; of settable means for detaining said type carriers out of cipher-setting position, means 115 for effecting successive release of the type carriers by the amount-determining devices; means for interrupting at will the successive release of said type carriers; and means for detaining type carriers in operation of the 120 totalizing means as determined by adjustment of said interrupting means.

10. In a machine of the character described, the combination of depressible amount keys and stop connections; a prime 125

- 3
- 5 mover; type carrying levers; racks having lost motion connection therewith; normally retracted pawls adapted to engage said type carrying levers; a handle-equipped cam structure to act collectively upon said pawls for moving them to engaging position; a series of normally retracted latches adapted upon such movement of said pawls to engage the same and take up positions in operative relation to the key connections; couplers movably mounted upon said latches respectively, a coupler on one latch engaging the next adjacent latch; and one or more handle-equipped shiftable members for displacing couplers.
- 10 11. In a machine of the character described, the combination of depressible amount keys and stop connections; slide strips operated by said keys, a prime mover; type carrying levers; racks having lost motion connection therewith; normally retracted pawls adapted to engage said type carrying levers; a handle-equipped cam structure to act collectively upon said pawls for moving them to engaging position; a series of normally retracted latches adapted upon such movement of said pawls to engage the same and take up positions in operative relation to the aforesaid slide strips; couplers movably mounted upon said latches respectively, a coupler on one latch engaging the next adjacent latch; and one or more handle-equipped shiftable members for displacing couplers.
- 15 12. In a machine of the character described the combination of depressible amount keys and stop connections; a prime mover; type carrying levers; racks having lost motion connection therewith; normally retracted swing pawls adapted to engage said type carrying levers; a handle-equipped rocking cam structure to act collectively upon said pawls for moving them to engaging position; a series of normally retracted pivoted latches adapted upon such movement of said pawls to engage the same and take up positions in operative relation to the key connections; couplers movably mounted upon said latches respectively, a coupler on one latch engaging the next adjacent latch; one or more handle-equipped shiftable members for displacing couplers; and levers operated by the aforesaid cam structure to retract the latches.
- 20 13. In a machine of the character described the combination of depressible amount keys and stop connections; slide strips operated by said keys; a prime mover; type carrying levers; racks having lost motion connection therewith; normally retracted swing pawls adapted to engage said type carrying levers; a handle-equipped rocking cam structure to act collectively upon said pawls for moving them to engaging position; a series of normally retracted latches adapted upon such movement of said pawls to engage the same and take up positions in operative relation to the key connections; couplers movably mounted upon said latches respectively, a coupler on one latch engaging the next adjacent latch; and one or more handle-equipped shiftable members for displacing couplers.
- 25 14. In a machine of the character described the combination of depressible amount keys and stop connections; slide strips operated by said keys; a prime mover; type carrying levers; racks having lost motion connection therewith; normally retracted pawls adapted to engage said type carrying levers; a handle-equipped cam structure to act collectively upon said pawls for moving them to engaging position; a series of normally retracted latches adapted upon such movement of said pawls to engage the same and take up positions in operative relation to the key connections; couplers movably mounted upon said latches respectively, a coupler on one latch engaging the next adjacent latch; and one or more handle-equipped shiftable members for displacing couplers.
- 30 15. In a machine of the character described, the combination of depressible amount keys and stop connections; a prime mover; type carrying levers; racks having lost motion connection therewith; normally retracted pawls adapted to engage said type carrying levers; a handle-equipped cam structure to act collectively upon said pawls for moving them to engaging position; a series of normally retracted latches adapted upon such movement of said pawls to engage the same and take up positions in operative relation to the key connections; couplers movably mounted upon said latches respectively, a coupler on one latch engaging the next adjacent latch; one or more handle-equipped shiftable members for displacing couplers; and levers operated by the aforesaid cam structure to retract the latches.
- 35 16. In a machine of the character described the combination with manipulative amount-determining devices, a prime mover, register wheels, type carriers, and racks thereon, the type carriers and racks being relatively movable for transfer purposes and for setting up ciphers; of normally retracted pawls adapted to engage said type carrying levers; a handle-equipped cam structure to act collectively upon said pawls for moving them to engaging position; a series of normally retracted latches adapted upon such movement of said pawls to engage the same and take up positions in operative relation to the key connections; couplers movably mounted upon said latches respectively, a coupler on one latch engaging the next adjacent latch; one or more handle-equipped shiftable members for displacing couplers; and levers operated by the aforesaid cam structure to retract the latches.

equipped shiftable members for displacing couplers; and tappet pieces adapted for operation by the racks and adapted to displace latches.

17. In a machine of the character described the combination with manipulative amount-determining devices, a prime mover, register wheels, type carriers, racks thereon, the type carriers and racks being relatively movable for setting up ciphers, and totalizing means; of normally retracted pawls adapted to engage said type carrying levers; a handle-equipped cam structure to act collectively upon said pawls for moving them to engaging position; a series of normally retracted latches adapted upon such movement of said pawls to engage the same and take up positions in operative relation to the key connections; couplers movably mounted upon said latches respectively, a coupler on one latch engaging the next adjacent latch; one or more handle-equipped shiftable members for displacing couplers; and pawl-setting devices carried by the totalizing means and settable by the said shiftable members.

18. In a machine of the character described the combination with manipulative amount-determining devices, a prime mover, register wheels, type carriers, racks thereon, the type carriers and racks being relatively movable for setting up ciphers, and totalizing means; of normally retracted pawls adapted to engage said type carrying levers; a handle-equipped cam structure to act collectively upon said pawls for moving them to engaging position; a series of normally retracted latches adapted upon such movement of said pawls to engage the same and take up positions in operative relation to the key connections; couplers movably mounted upon said latches respectively, a coupler on one latch engaging the next adjacent latch; one or more handle-equipped shiftable members for displacing couplers; pawl-setting devices carried by the totalizing means and settable by the said shiftable members; and levers for retracting the latches, said levers operated by said shifting members when the latter set the aforesaid devices carried by the totalizing means.

19. In a machine of the character described the combination with manipulative amount-determining devices, a prime mover, register wheels, type carriers, racks thereon, the type carriers and racks being relatively movable for setting up ciphers, and totalizing means; of normally retracted pawls adapted to engage said type carrying levers; a handle-equipped cam structure to act collectively upon said pawls for moving them to engaging position; a series of normally retracted latches adapted upon such movement of said pawls to engage the same and take up positions in operative relation to the

key connections; couplers movably mounted upon said latches respectively, a coupler on one latch engaging the next adjacent latch; one or more handle-equipped shiftable members for displacing couplers; pawl-setting devices carried by the totalizing means and settable by the said shiftable members; and levers for retracting the latches, said levers operated by said shifting members when the latter set the aforesaid devices carried by the totalizing means and also operable by the aforesaid cam structure.

20. In a machine of the character described the combination of depressible amount keys and stop connections; a prime mover; type carrying levers; racks having lost motion connection therewith; normally retracted pawls adapted to engage said type carrying levers; a handle-equipped cam structure to act collectively upon said pawls for moving them to engaging position; a series of normally retracted latches adapted upon such movement of said pawls to engage the same and take up positions in operative relation to the key connections; couplers movably mounted upon said latches respectively, a coupler on one latch engaging the next adjacent latch; and one or more handle-equipped slides having portions adapted to act upon the couplers to displace the same.

21. In a machine of the character described, the combination with manipulative amount-determining devices, a prime mover, register wheels, type carriers, racks thereon, the type carriers and racks being relatively movable for setting up ciphers, and totalizing means; of normally retracted pawls adapted to engage said type carrying levers; a handle-equipped cam structure to act collectively upon said pawls for moving them to engaging position; a series of normally retracted latches adapted upon such movement of said pawls to engage the same and take up positions in operative relation to the key connections; couplers movably mounted upon said latches respectively, a coupler on one latch engaging the next adjacent latch; one or more handle-equipped slides having portions adapted to act upon the couplers to displace the same; and pawl-setting devices carried by the totalizing means and adapted to be acted upon by other portions of said slides upon extreme movement thereof whereby to move said devices into operative relation with the pawls.

22. In a machine of the character described, the combination of keys and their stop connections; type carrying levers and racks having lost motion connection therewith; totalizing means; an oscillatory prime mover having a tappet stud; swinging pawls for detaining the type carrying levers; a bail to act on said pawls having an

- arm with pivoted spring-actuated tappet piece to coact with the said tappet stud of the prime mover; a rock shaft operated by the totalizing means and having an arm between which and said tappet pawl there is a cam and lost motion engagement; a handle-equipped member for collectively throwing the swinging pawls to effective position; latches for holding them therein; couplers between latches; means for tripping the latches by the key connections; and means for displacing the couplers.
23. In a machine of the character described, the combination of type carriers normally withheld from printing position; settable means for additionally and individually restraining them; manipulative amount-determining devices; means operated thereby for relieving the type-carriers from the restraint imposed upon them by said settable means; and means for release of type-carriers in groups.
24. In a machine of the character described, the combination of type-carriers normally withheld from printing position; settable means for additionally restraining them; manipulative amount-determining devices; means operated thereby for relieving the type-carriers from the restraint imposed upon them by said settable means; and means for release of type-carriers in groups.
